UNITED STATES PATENT OFFICE.

CHARLES S. DEMAREST, OF BROOKLYN, NEW YORK, ASSIGNOR TO AMERICAN TELEPHONE AND TELEGRAPH COMPANY, A CORPORATION OF NEW YORK.

TELEPHONE REPEATER EQUIPMENT.

1,386,321.

Specification of Letters Patent. Patented Aug. 2, 1921.

Application filed May 9, 1919. Serial No. 295,912.

To all whom it may concern:

Be it known that I, CHARLES S. DEMAREST, residing at Brooklyn, in the county of Kings and State of New York, have invented certain Improvements in Telephone Repeater Equipments, of which the following is a specification.

This invention relates to transmission circuits which include repeaters and more particularly to a means for testing such repeaters.

When a transmission line includes repeater apparatus it is customary to associate with the repeater artificial lines or net works suitable for balancing the sections of the transmission line in order to prevent the repeater from "singing." To test the transmission gain due to the repeater, the repeater apparatus including the artificial lines is disconnected from the transmission line and connected to a standard form of testing apparatus. This testing apparatus will have a constant impedance which in all probability will not be the same as that of the sections of the transmission line which are interconnected by the repeater apparatus. Accordingly when the testing apparatus is connected to the repeater, the artificial lines will not balance the testing apparatus and will no longer maintain the repeater in a balanced condition and "singing" in the repeater will result.

It is an object of the invention to avoid or obviate the above described difficulties when testing repeater apparatus and accordingly, the said invention provides testing apparatus which may be associated with repeater elements in a line without causing "singing" to take place in said repeater elements. This is accomplished by associating with the switching means, whereby the repeaters are disconnected from the transmission line and connected to the testing apparatus, means for disconnecting from the repeaters the balancing artificial lines normally associated with the repeaters and for associating with the repeaters artificial lines suitable for balancing the testing apparatus. Other and further features of the invention will be clear from the detailed description and drawing of the invention.

In the drawing is illustrated a preferred form of the arrangements embodying this invention. The two sections L_1 and L_2 of a transmission line are shown interconnected

by repeater apparatus. The repeater apparatus includes the repeater elements R_1 and R_2 which are shown as of the mechanical type, although any other type, such as the well known vacuum tube repeater, may be employed. Normally associated with the repeater apparatus are the net works N_1 and N_2 adapted for balancing the sections L_1 and L_2 respectively of the transmission line, in order to prevent the repeater from "singing." Associated with sections L_1 and L_2 of the line are the jacks J_1 and J_3 . When the plugs P_1 and P_3 of patching cords are inserted in the jacks J_1 and J_3 respectively, the repeater apparatus may be disconnected from the line and connected with the testing apparatus. The patching cords are associated with the testing apparatus by means of the jacks J_2 and J_4 . When the repeater apparatus is disconnected from sections L_1 and L_2 of the line, the net works N_1 and N_2 are disconnected from the repeater apparatus and the net works N_3 and N_4 are connected to the repeater apparatus. The net works N_3 and N_4 are of a value suitable for balancing the impedance of the testing apparatus. Associated with the jacks J_2 and J_4 of the testing apparatus are conductors 12 and 13, respectively. Included in these conductors are the net works N_5 and N_6 which are of a value adopted as a standard for purposes of comparison and testing.

The conductors 12 and 13 are normally associated with the contacts of the key K_1 . When the key K_1 is operated, the generating apparatus 35 which is adapted to generate currents suitable for testing purposes, such, for example, as currents of telephonic frequency, will be started in operation. Testing current may then be applied either over conductors 12, through the repeater apparatus and over conductors 13, to the receiver shunt 31 and the operator's telephone set 32, or from the generating apparatus 35 over conductors 13, through the repeater apparatus and over conductors 12 to the receiver shunt 31 and the telephone receiver 32. A key K_2 is provided in the testing apparatus upon the operation of which the testing current may be transmitted from the generating apparatus 35 through the net work N_7 and to the telephone receiver 32. By means of comparing the transmission efficiency, as indicated by a scale on the receiver shunt apparatus, between the circuit including the net

work N_7 , and the circuit including the repeater apparatus, a means is afforded for measuring the gain in transmission over a circuit due to the including therein of the repeater apparatus.

The operation of the invention is as follows: If it is desired to test the gain in transmission due to the including in the line of the repeaters R_1 and R_2 , the plugs P_1 and P_2 are inserted in the jacks J_1 and J_2 , and the plugs P_3 and P_4 are inserted in the jacks J_3 and J_4 , respectively. The repeater apparatus is now entirely disconnected from the transmission line and the section L_1 is connected with the section L_2 of the line over the make contacts of jacks J_1 and J_3 and over conductors 3 and 4. When the plugs P_1 and P_2 are inserted in the jacks J_1 and J_2 , the following circuit is closed: from ground, sleeve contacts of jack J_2 , and plug P_2 , sleeve conductors of the patching cord, sleeve contacts of plug P_1 and jack J_1 , sleeve conductors of jack J_1 , over conductor 46, winding of relay 1, to battery and ground. The closing of this circuit will operate the relay 1 which will pull up its armatures and will disconnect from the repeater R_1 the net work N_1 , which is normally connected thereto, and will connect the net work N_3 over conductors 10, contacts of relay 1 and over conductors 6 to the windings of the usual transformer 5 of the repeater apparatus. When the plugs P_3 and P_4 are inserted in the jacks J_3 and J_4 , respectively, the following circuit is closed: from ground, sleeve contacts of jacks J_4 and plug P_4 , sleeve conductors of the patching cord, sleeve contacts of plug P_3 and jack J_3 , over the sleeve conductors of jack J_3 and over conductor 47, winding of relay 2, to battery and ground. The closing of this circuit will energize relay 2 which will pull up its armatures and disconnect from the repeater R_2 the net work N_2 , which is normally connected thereto, and will connect the net work N_4 over conductors 11, contacts of relay 2, and over conductors 7, to the windings of the usual transformer 45 associated with the repeater apparatus. The keys K_1 and K_2 will now be thrown. The operation of the key K_1 closes the following circuit: from ground, make contact of key K_1 , conductor 24 to the generating apparatus 35. The closing of this circuit will start the generating apparatus 35 into operation. The operation of the key K_2 will close the following circuit: from ground, upper make contact of key K_2 , conductor 18, winding of relay 17, to battery and ground. The operation of key K_2 will also close the following circuit: from ground, lower make contact of key K_2 , conductor 19, winding of relay 16, to battery and ground. The closing of these two last mentioned circuits will operate the relays 16 and 17. When the generating ap-

paratus 35 is started in operation and when the relays 16 and 17 are operated, testing current will be applied from the generating apparatus 35 over the following circuit, the key K_1 being thrown to the left: over conductors 22, over conductors 61, left hand make contacts of key K_1 , over conductors 20, contacts and armatures of relay 16, over conductors 14, net work N_7 over conductors 15, armatures and contacts of relay 17, over conductors 21, right hand normal contacts of key K_1 , over conductors 25 and 26, from conductor 25 to the receiver 32, and from conductor 26, over conductor 28, make contact of key K_2 , over conductor 27, to the receiver 32. It is pointed out that the receiver shunt 31 is not included in this last mentioned circuit as the operation of key K_2 closes the short-circuit about the series resistance 34 and opens the path including the shunt resistance 33. By means of the receiver 32, the volume of the sound transmitted over this last mentioned circuit may be observed. The key K_2 will now be restored to normal. The testing current from the generating apparatus 35 will now be transmitted over the following circuit: from the generating apparatus 35, over conductors 22, over conductors 61, left hand make contacts of key K_1 , over conductors 20, net work N_5 , over conductors 12, tip contacts of jack J_2 and plug P_2 , tip conductors of patching cord, tip contacts of plug P_1 and jack J_1 , through the repeater apparatus in the usual manner, to the tip contacts of jack J_3 and plug P_3 , over the tip conductors of the patching cord, tip contacts of plug P_4 and jack J_4 , over conductors 13, net work N_6 , normal contacts of relay 17, conductors 21, right hand normal contacts of key K_1 , over conductors 25 and 26, through the receiver shunt 31, to the telephone receiver 32. By now adjusting the receiver shunt until the same tone is heard in the receiver as in the case of the formerly traced circuit through the net work N_7 , it will be possible to observe and measure from the graduated scale on the receiver shunt the gain due to the including in the circuit of the repeater apparatus. By throwing the key K_1 in the opposite direction, a testing current may be transmitted through the repeater apparatus in the opposite direction. By this means the gain in transmission over the transmission line in either direction, due to the repeater apparatus, may be observed and measured. As has been previously pointed out, the net works N_3 and N_4 which are associated with the repeater apparatus, when the testing apparatus is associated therewith, are adapted for balancing the impedance of the testing apparatus and a condition of balance in the repeater apparatus will be maintained with respect to the testing apparatus when the testing apparatus is connected thereto.

Accordingly, the transmission of testing current from the testing apparatus through the repeater apparatus will not cause "singing" to take place in the repeater apparatus.

5 While the invention has been disclosed as embodied in certain specific arrangements which have been deemed desirable, it is understood that it is capable of embodiment in many and widely varied forms without 10 departing from the spirit of the invention as defined in the appended claims.

What is claimed is:

1. A transmission circuit including lines interconnected by repeater apparatus, networks 15 normally connected to said repeater apparatus for balancing said lines, apparatus for testing said repeater apparatus, networks associated with said repeater apparatus for balancing said testing apparatus, 20 and means responding when said testing apparatus is connected to said repeater apparatus for disconnecting said first mentioned networks from said repeater apparatus and for connecting said second mentioned networks thereto.

2. A transmission circuit including lines interconnected by a telephone repeater, networks normally connected to said repeater for balancing said lines, apparatus for testing 30 said repeater, networks associated with said repeater for balancing said testing ap-

paratus, switching means associated with said lines and said testing apparatus, means controlled by said switching means for disconnecting said repeater from said lines and 35 for interconnecting said lines over auxiliary conductors, and means controlled by said switching means for disconnecting said first mentioned networks from said repeater and for connecting said second mentioned net- 40 works thereto.

3. A transmission circuit including lines interconnected by a telephone repeater, networks normally connected to said repeater for balancing said lines, apparatus for testing 45 said repeater, networks associated with said repeater for balancing said testing apparatus, jacks associated with said lines and said testing apparatus, patching cords adapted to coöperate with said jacks and connect 50 said testing apparatus with said repeater, relay means associated with the jacks of said lines and responding when said testing apparatus is connected to said repeater for disconnecting said first mentioned networks 55 from said repeater and for connecting said second mentioned networks thereto.

In testimony whereof I have signed my name to this specification this 5th day of May, 1919.

CHARLES S. DEMAREST.
